(57) **CLAIM**

The ornamental design for a wearable blanket, as shown and described.

DESCRIPTION

FIG. 1 is a perspective view of a wearable blanket, showing my new design;

FIG. 2 is another perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depict portions of the wearable blanket that form no part of the claimed design.

The cross-hatched lines and shade lines in the drawings illustrate shading of the wearable blanket and do not reflect a particular surface ornamentation or material.
